UNITED STATES PATENT OFFICE.

JOHN BODEN RADFORD, OF VALOIS, QUEBEC, CANADA, ASSIGNOR TO WESTERN ELECTRIC COMPANY, INCORPORATED, OF NEW YORK, N. Y., A CORPORATION OF NEW YORK.

SWITCHING DEVICE.

Application filed June 16, 1920. Serial No. 389,279.

To all whom it may concern:

Be it known that I, JOHN BODEN RADFORD, a subject of the King of Great Britain, residing at 45 Queens Road, Valois, in the 5 Province of Quebec and Dominion of Canada, have invented certain new and useful Improvements in Switching Devices, of which the following is a full, clear, concise, and exact description.

10 This invention relates to electrical switching devices.

The object of the invention is to provide an improved switching device for use in normally closed circuits which shall be simple 15 in construction and positive in its operation.

The invention is particularly adaptable in main line circuits in which there are a plurality of local circuits connected in series with these main line circuits.

20 The invention in its preferred form, provides a plug switch which is adapted to be inserted in an outlet switch box. Conductive means are provided on the plug to connect line terminals with local circuit terminals.

25 The switch box is provided with spring members which, when the plug is removed, contact to connect the line terminals. These spring members are separated by cooperating members attached to the plug. Means is

30 also provided in the plug whereby, when the line voltage exceeds a certain predetermined maximum, the circuit is reestablished across the line terminals to short circuit the local circuit.

35 The invention will be better understood by reference to the drawings. Fig. 1 represents a front view of the terminal box with the plug removed and portions of the cover cut away; Fig. 2 shows a cross section of the box

40 along the plane indicated by the reference character 2; Fig. 3, shows a cross sectional view at the plane 3, of the box with the plug removed; Fig. 4, shows a bottom view of the plug, and Fig. 5 discloses a circuit wherein

45 the terminal box and plug may be used to advantage. Like reference characters refer to like parts in the various figures.

A terminal box 1, made of insulating material is provided with terminal lugs 4, 5, 6 and 7 mounted in the interior thereof, which terminal lugs are secured to conductive bars 8, 9, 10 and 11 respectively, by means of the screws 12. The bars 8, 9, 10 and 11 are fastened to the frame of the box 55 1 by means of screws 13. Cables 14 and 15

enter the box 1 through openings in the bottom thereof and are attached to the bars 8 and 9 respectively by means of lugs 16 and 17. Cables 14 and 15 may be entered into the box 1 in any suitable manner. In the 60 preferred form they are shown entering through short lengths of pipe 18 screwed into the frame of the box 1. The voids between the cable and the box 1 are filled by a quantity of insulating cement 19 which is 65 introduced through an aperture 20. The aperture 20 is thereafter filled by a screw plug 21. Conductors 22 and 23 are attached to the bars 11 and 10 respectively in a manner similar to that in which cables 14 and 70 15 are attached to bars 8 and 9. Terminal lugs 4, 5, 6 and 7 are formed of bent, flat, springy material and in such a form that they are adapted to receive a flat conductor bar into their jaws. The two spring members 24 are fastened under terminal lugs 4 and 5 and bent in such a manner that they 75 present a good flat conductive surface to each other.

It will thus be seen that normally the 80 cables 14 and 15 are electrically connected by the springs 24. A plug comprising a base 25, of suitable insulating material, supports the two bars 26 and 27 on projections 28. These bars 26 and 27 are adapted to 85 connect terminal lugs 5 and 6 and lugs 7 and 8 respectively when the plug is inserted into the box 1. Two spring members 29, are also supported by the projections 28 on the base 25, and are bent so as to meet midway 90 between the bars 26 and 27 and present to each other a good flat conductive surface. Between the opposing faces of the spring members 29 is placed a thin sheet of dielectric material 30 which normally serves 95 to prevent the passage of current across the spring members 29. The opposing ends of the springs 29 are adapted to fit between the opposing faces of the spring 24 when the plug is inserted in the box 1 thereby breaking the contact between spring members 24. 100

When the plug is inserted into the terminal box 1, the bars 26 and 27 connect the terminal lugs 5 and 6, and 7 and 8 respectively, and the spring members 29 separate the spring members 24 whereby the circuit is changed to include the conductors 22 and 23. 105

A handle 31 of any suitable form is provided on the plug. A face plate 32 is pro- 110

vided to fit into the aperture of the box 1 and is fastened thereto by means of bolts 33. The face plate 32, is provided with an outwardly threaded portion 34 onto which 5 is screwed a cover 35 to enclose the box.

In the circuit shown in Fig. 5, lamps 39, 40 and 41, are adapted to be connected in series in the circuit of which 37 and 38 are the main line conductors. The lamps 39 10 and 41 complete the circuit through the terminal boxes 42 and 44. Lamp 40, however, being removed as shown, the plug of the terminal box 43 is also removed and the circuit is closed through the springs 36. 15 Should the voltage in the main line become excessive, the dielectric material 30 would be broken down and the circuit completed through spring members 24 thus protecting the lamp 39 from damage.

20 What is claimed is:

1. In an electrical switching device, a pair of line terminals, a pair of local circuit terminals, a pair of conductive spring members to connect the line terminals, a plug 25 switch comprising members for connecting the line terminals with the local circuit terminals, and an arm electrically connected with each of said members and separated by dielectric material and adapted to be inserted 30 between the pair of conductive spring members.

2. In an electrical switching device, a pair of line terminals, a pair of local circuit terminals, a pair of conductive spring members to connect the line terminals, and a plug switch comprising a pair of conductive bars to connect the line terminals with the local circuit terminals and a spring member 35 mounted with each said conductive bar, separated from each other by a sheet of dielectric material and adapted to be inserted between the first pair of spring members.

3. An electrical switching device comprising

ing a casing provided with a plurality of holes in the top and bottom for the introduction of conductor wires and an orifice in the front thereof, a pair of line terminals and a pair of local circuit terminals disposed within the casing, a pair of spring conductors mounted with the line terminals 45 and normally engaging each other to electrically connect them, a plug member comprising a base to fit into the orifice in the front of the casing, a pair of conducting bars to connect the line and local circuit 50 terminals, and a member mounted with each said conducting bar and separated from each other by dielectric material and adapted to be inserted between the first said 55 spring conductors, and a cover for the orifice and the plug.

4. An electrical switching device, comprising a casing provided with a plurality of holes in the top and bottom for the introduction of conductor wires, and a circular orifice in the front thereof; a pair of line terminals and a pair of local circuit terminals disposed within the casing; a pair of spring conductors mounted with the line terminals and normally engaging each other 65 to electrically connect them; a plug member comprising a circular base to fit into the orifice in the front of the casing, a pair of conductive bars to connect the line terminals with the local circuit terminals, and a spring member mounted with each said conductive bar, separated from each other by a sheet of dielectric material and adapted to be inserted between the first said spring conductors; and a screw cover closing the orifice and covering the plug.

In witness whereof, I hereunto subscribe my name this eighteenth day of April, A. D. 1921.

JOHN BODEN RADFORD.
